UNITED STATES PATENT OFFICE

LEWIS T. CANFIELD, OF CHICAGO, ILLINOIS, ASSIGNOR TO UNION DRAFT GEAR COMPANY, OF CHICAGO, ILLINOIS, A CORPORATION OF ILLINOIS.

DRAFT-GEAR.

1,112,767.

Specification of Letters Patent. Patented Oct. 6, 1914.

Application filed July 8, 1910. Serial No. 571,044.

To all whom it may concern:

Be it known that I, LEWIS T. CANFIELD, citizen of the United States, residing at Chicago, in the county of Cook and State of Illinois, have invented a certain new and useful Improvement in Draft-Gear, of which the following is a full, clear, concise, and exact description, reference being had to the accompanying drawings, forming a part of this specification.

My invention relates to draft gears and has for its object the provision of an improved draft gear construction whereby lighter pulling strains and the initial parts of heavier pulling strains are opposed by resisting mechanism that offers less opposition to the pulling strains than do the major draft strain opposing portions of the gears.

A device constructed in accordance with the invention preferably includes a coupler, mechanism for defining a normal position of the coupler when not subject to pulling or pushing strains, and mechanism limiting the forward and rearward movements of the coupler and serving to permit greater forward movement of the coupler from normal position than the maximum rearward movement of the coupler from normal position. As I have actually embodied my invention, I employ a coupler, mechanism for defining a normal position of the coupler when not subject to pulling or pushing strains, spring mechanism yieldingly connecting the coupler with the rear of the aforesaid mechanism to be subject to pulling strains, and mechanism operating independently of said spring mechanism for limiting the rearward movements of the coupler.

A very important feature of my invention, as preferably practised, resides in a yielding connection interposed between the coupler and mechanism that is employed to define a normal position for the coupler when not subject to pulling or pushing strains.

I will explain my invention more fully by reference to the accompanying drawing showing the preferred embodiment thereof as applied to the type of draft gear shown in Patent No. 861,636, granted July 30, 1907, to James R. Cardwell, though I do not limit myself to the type of draft gear shown in said patent.

In the drawing, Figure 1 is a plan view showing the preferred embodiment of the

invention, some parts being shown in section; and Fig. 2 is a central sectional elevation of the structure shown in Fig. 1, some of the parts being shown in full elevation.

Like parts are indicated by similar characters of reference in both figures.

It will not be necessary to describe in detail the mechanism that is relied upon to furnish the greater opposition to the pulling and pushing strains exerted upon the coupler ⁶⁰ *a* and which is employed to give said coupler a normal position when not subject to such strains, as the mechanism illustrated is now well known to those skilled in the art. In the embodiment of the invention illustrated, the coupler *a* has a shank *b* united with a well known form of coupler yoke *c* to which the invention is not to be limited. The coupler yoke shown embraces two pocketed follower plates *d* into which friction members *e* extend, these friction members co-operating with the spring mechanism *f*, friction blocks *f'*, and pocketed follower plates *d* to give the coupler a normal position when not under strain and occasion ⁷⁰ the production of friction when the heavier pulling and pushing strains are encountered by the coupler, as set forth in the aforesaid patent, the lighter pulling strains and the initial parts of the heavier pulling strains ⁸⁰ being opposed by spring mechanism *g* as will be hereinafter stated.

The friction producing mechanism of the draft gear is shown as being interposed between center sills *h* *h*. The rear follower plate *d* is shown as in engagement with the abutment lugs *i* and the forward follower plate is shown as in engagement with the abutment lugs *k*, these abutment lugs being mounted upon the inner faces of the center ⁹⁰ sills. The pushing strains that are heavy enough to move the forward follower plate are resisted by the action of the friction producing mechanism and the spring mechanism *f*, the rear abutments *i* holding the ⁹⁵ rear follower plate to position the same and thereby enable the friction and spring mechanism *f* to work. When pulling strains are exerted upon the coupler that are too light to effect the operation of the friction producing mechanism, then the yielding element *g* that is interposed between the rear of the friction producing mechanism and the coupler may cushion such light pulling strains. This interposed spring member *g* ¹⁰⁰ ¹⁰⁵ ¹¹⁰

also serves yieldingly to oppose the initial parts of the heavier pulling strains, whereafter the remainder of the heavier pulling strains are permitted to operate the friction producing device which has been described. In order to relieve the spring mechanism *g* of the function of transmitting the heavier pulling strains to such friction producing mechanism, I employ a rigid member *l* for transmitting the pulling strains when the spring mechanism *g* has performed its function of yieldingly opposing the initial parts of such strains. This rigid member *l* is desirably in the form of a barrel for housing the springs and desirably is adapted directly to engage a plate *m* resting against the rear follower plate and spaced apart at *n* from the rigid member a distance which it is desired to have the springs *g* yield before the pulling strains are directly applied to the friction producing portion of the gear. A bolt *o* passes through the spring barrel *l* and is fixed with relation to the plate *m*, this bolt being in sliding relation with the closed end of the spring barrel and the contiguous end of the yoke *c*. The abutment cheek plates *i* directly engage the rear follower plate *d*, whereby the spring mechanism *g* is not interposed between the rear follower plate and said abutments. The abutments *i* thus constitute mechanism operating independently of the spring mechanism *g* for limiting the rearward movements of the coupler, whereby the spring mechanism which is so serviceable in yieldingly opposing the lighter pulling strains and the initial parts of the heavier pulling strains does not have its efficiency impaired by being subject to violent pushing strains exerted upon the coupler. The set of the

springs *g* is not subject to that impairment which might be possible if the rigid structure *l* were not employed to transfer the heavier pulling strains to the friction producing mechanism of the gear. Preferably a key *p* is passed through the bolt *o* in rear of the coupler yoke *c* to limit the forward movement of the bolt through the coupler yoke.

While I have herein shown and particularly described the preferred embodiment of my invention, I do not wish to be limited to the precise details of construction shown, as changes may readily be made without departing from the spirit of the invention, *wt*, *mt*, *55*

Having thus described my invention, I claim as new and desire to secure by Letters Patent the following:—

In a draft gear, in combination, front and rear main followers, buffering mechanism reacting between such followers, a draw-bar yoke extending about the main followers and in rear of the rear main follower, a pair of supplemental followers interposed between the rear end of the yoke and the rear main follower, a spring reacting between the supplemental followers, and a bolt fixed in the forward one of the supplemental followers and extending rearwardly therefrom through and in sliding relation with the rear supplemental follower and the rear end of the yoke, and a key limiting the forward sliding movement of the bolt with respect to the yoke.

In witness whereof, I hereunto subscribe my name this fifth day of July, A. D., 1910.

LEWIS T. CANFIELD.
